CLAIM

The ornamental design for a container for liquids, substantially as shown and described:

DESCRIPTION

FIG. 1 is a front elevational view of a container for liquids showing our new design;

FIG. 2 is a rear elevational view thereof;

FIG. 3 is a top plan view thereof;

FIG. 4 is a bottom plan view thereof;

FIG. 5 is an elevational view thereof looking from the right of FIG. 1;

FIG. 6 is an elevational view thereof looking from the left of FIG. 1;

FIG. 7 is a top perspective thereof with a closure being shown in broken lines to illustrate environmental use only; and

FIG. 8 is a partial cross-sectional view thereof taken on line 8—8 of FIG. 4.

FIG. 1.

FIG. 2.

FIG. 3.

FIG. 8.

FIG. 5.

FIG. 6.

FIG. 7.

FIG. 4.
